HOIST STRUCTURE

James R. Coffing, Danville, Ill.

Application April 21, 1951, Serial No. 222,257

7 Claims. (Cl. 254—167)

1

This invention relates to a hoist structure of the ratchet type which is capable of load raising, controlled load lowering and free running action, reference being made to my application for Letters Patent Serial No. 129,071, filed November 23, 1949.

It is the object of this invention to provide a simplified hoist having a reversely biased holding pawl manually controlled to bias said pawl to ratchet engaging position during load raising, and normally bias it out of ratchet engagement while permitting it to be positively moved into ratchet engagement during load lowering. This is accomplished through the medium of a control ring in camming engagement with said pawl such as to normally permit free ratcheting action, but forcibly move it against spring tension into ratchet engagement upon completion of a load lowering stroke.

This invention further provides for latching the load pawl out of ratchet engagement during its return stroke of the load lowering operation through the medium of said control ring, with a manually adjustable pin operable to unlatch said pawl into ratchet engagement at the beginning of a lowering operation, when in one position, and cause it to remain latched for reversing the handle position, when in another position.

A further feature of the invention resides in the manual biasing of the holding pawl out of ratchet engagement and camming the load pawl out of ratchet engagement by the control ring to permit of free camming action.

The full nature of the invention will be understood from the accompanying drawings and the following description and claims:

Fig. 1 is a side elevation of the hoist structure embodying my invention.

Fig. 2 is a sectional view taken on the line 2—2 of Fig. 1.

Fig. 3 is a detail sectional view taken on the line 3—3 of Fig. 2.

In the drawings I have illustrated a hoist structure which comprises a modification of the invention disclosed in my copending application, Serial No. 129,071, filed November 23, 1949, wherein there is provided a housing 63 having the usual swivel supporting hook 64. This housing 63 has mounted therein a rotatable load wheel 69 carrying a shaft 65, which has one end supported in an offset bearing 66 forming a part of the housing. Intermediate of its ends the shaft 65 is supported on a face plate 67 of the housing, and projects a considerable distance beyond the face plate for carrying the ratchet wheel 68. That portion of the shaft mounted within the housing,

which housing is open on its lower side, carries the load wheel 69 over which is adapted to pass a hoist chain 70.

Mounted on the front face of the plate 67 is a holding pawl 71, which is adapted to engage the teeth of the ratchet wheel 68 for the purpose of holding the same against reverse rotation. This holding pawl is pivotally mounted on a supporting pin 72, which is mounted in a recess in a lug 73 extending from the front face of the plate 67. The holding pawl is biased in engaging position through the means of a coiled spring 74 wrapped around the pin 72 and having one end bearing on one end of a pin 75 extending through the pawl 71, see Fig. 2. The opposite end 76 of this spring is fastened in a pin 77 on a rotatable head 78. The head is mounted upon a shaft 79, which extends through the housing and carries at its opposite end an adjusting handle 80 see Fig. 1. The head 78 is provided with an extension 81 having an offset lug 82 (Fig. 2). The extension 81, when the head is rotated in one direction, engages a stop 83 to prevent further rotation thereof; and when the head 78 is rotated in an opposite direction, the offset portion 82 engages against the end 76 of the spring, thereby providing a stop for the head 78 in the opposite direction.

With the head 78 and its pin 77 in the position illustrated in Fig. 2 the spring has a biasing effect on the holding pawl 71 to bias the pawl into engagement with the teeth of the ratchet 68. However, if the head 78 is rotated in a counterclockwise direction, the pin 77 is rotated over center to a position where the portion 82 bears against the spring, and the spring will be effective to bias the holding pawl 71 out of engagement with the teeth of the ratchet 68. Under normal loading raising conditions, the head is rotated clockwise to occupy the position illustrated in Fig. 2, which is the position to cause the spring to bias the pawl into engaging position. As a result, as the shaft 65 and with it the ratchet wheel 68 is rotated counterclockwise, in the load raising direction, the holding pawl will ratchet over the teeth to permit this rotation; but at the same time will drop into position to lock the ratchet wheel 68 and its shaft 65 against clockwise rotation.

Rotatably mounted on that portion of the shaft 65 which extends beyond the ratchet wheel is an operating handle 84, see Fig. 1. This handle is provided with a housing or hub portion 85 having a bearing 86 to accommodate the end of the shaft 65. The handle has mounted within

the housing an operating load pawl 87 pivoted upon a pivot pin 88, see Fig. 2, extending between the two side walls of the housing 85. This load pawl 87 is adapted to cooperate with the teeth of the ratchet wheel 68 for controlling the rotation of the shaft 65, and with it the load wheel. The load pawl is biased in its engaging direction through the medium of a spring 89, one end of which is hooked over the back side of the pawl. A portion of the spring 89 is wound around a stationary pin 90 fixedly secured between the walls of the handle housing portion. In addition to the load pawl 87 there is mounted on the hub portion 85 a pawl controlling latch 91 pivotally mounted on a pin 91' fixedly secured in one wall of the hub portion. The latch 91 is provided with a pin receiving latching notch 92. Under predetermined conditions a pin 94 on the load pawl 87 engages in notch 92 and maintains the load pawl in non-operating condition. The pawl controlling latch 91 is biased in a direction to cause the latching notch 92 to engage and hold the pin 94 through the medium of the end 95 of the coiled spring 89, which end is adapted to engage over a pin 96 in the face of the latch 91.

Adjacent the face of the ratchet wheel 68, see Fig. 2, is a control ring 97 which is provided with a radially extending arm 98 slotted as at 99 to receive a projection of the pin 75 on the holding pawl 71. This arm 98 has a camming face 102 adapted, under predetermined conditions, to engage a pin 104 on the face of the load pawl 87. This ring is also provided, at a point opposite the arm 98, with a second arm 105 likewise, under predetermined conditions, adapted to be engaged by the pin 104 on load pawl 87.

Extending through the housing 63 is a transversely movable pin 106, see Fig. 3, the end 107 of which is, under normal operation, adapted to lie in the path of the latch 91. This pin 106, however, may be moved transversely through the medium of an operating handle 108 so that the end 107 is withdrawn from the path of the latch 91. The head 108, see Fig. 3, is shouldered as at 109 to, by partially rotating the pin, engage over the face of the shoulder portion 110 of the housing to retain the pin 106 in its retracted position against the influence of a biasing spring 111, which normally biases the pin in a position to project its end 107 in its normal or projected path.

In normal operation, and for the purpose of description, the hoisting operation may be considered as the normal operation of the hoist, with the spring control head 78 rotated to the position illustrated in Fig. 2, the coiled spring 74 is in a position to bias the holding pawl 71 into engagement with the teeth of the ratchet 68. Likewise, the spring portion 89 will normally bias the load pawl 87 in a direction to engage the teeth of the ratchet 68. Accordingly, with a load on the hoisting chain, the holding pawl in engagement with the ratchet 68 will hold the shaft 65, and with it the load wheel, against clockwise rotation under the load. By elevating the handle, the pawl 87 will ratchet over the wheel 68 until the handle has reached near the uppermost limit of its stroke. At this time, as soon as the down-stroke of the handle is effected, the pawl 87 will engage the ratchet teeth rotating the ratchet wheel and the load wheel in a counterclockwise direction causing the chain to operate to hoist the load. As soon as the handle has moved downward to the limit of its normal operating stroke, the pawl 71 engaging the ratchet 68 will

hold the ratchet against rotation in a clockwise direction, accordingly holding the load from dropping. The handle 84 may be raised for another stroke, the pawl 87 ratcheting over the teeth until the handle reaches the uppermost part of its stroke. The latch 91, on the downward stroke of the handle, will engage the projection 107 and, accordingly, will be thrown into such a position that there is no danger of the latching notch 92 catching and holding the pin 94, so that there will be no impedance in the normal operation of the pawl 87.

If now it be desired to lower the load under control, the adjusting handle 80 is swung to rotate the head 78 counterclockwise until the offset lug 82 engages the spring portion 76. This places the spring 74 under tension in the reverse direction to bias the pawl 71 out of engagement with the ratchet teeth of the ratchet 68. If the handle is raised to the uppermost limit of its stroke, pin 104 will strike the face 102 of the arm 98 and in doing so will rock the ring 97 in a clockwise direction, and in a direction so that the slot 99 operating on pin 75 on the holding pawl 71 will move this pawl into engagement with a tooth of the ratchet 68, and in a position to hold the ratchet from rotation under load on the chain. At the same time the pin 104 upon striking the face 102 of the arm 98, will rock the holding pawl 87 on its pivot until the latching notch 92 on the latch 91 will engage the pin 94 on the pawl 87 holding the pawl in its disengaged position. Therefore, as the handle is rocked downwardly the load pawl 87 will be free to move over the ratchet 68 until the handle reaches its lowermost position. When the handle reaches its lowermost position, the latch 91 will strike the projection 107 of the pin 106 throwing the latch out of engagement with the pin 94, thereby releasing the load pawl so that it can be biased into engagement with a tooth of the ratchet 68 and in a position to control the lowering of the load. In this position a slight downward movement of the handle will rotate the ratchet slightly to relieve the holding pawl of pressure so that the holding pawl may move into disengaged position permitting the shaft to rotate clockwise under control of load pawl 87.

It is to be remembered that with the spring 50 biasing the holding pawl 71 normally out of engaging position as in the case of lowering, if it be desired to have a free chain operation of the load wheel, the handle after having moved to the limit of its utmost position to release pawl 71, as heretofore described, may be lowered but short of and not to the extent that latch 91 will engage the projection 107. Thus the latch 91 will retain pawl 87 in its disengaged position. Under these circumstances, the holding pawl and the operating pawl are both inoperative, and the load wheel is free to rotate without obstruction.

If it be desired to operate the device with the handle operating from the right side, as distinguished from the left side as shown in the drawings, the handle 84 is raised sufficiently high for the pin 104 to engage the face 102 of the arm 98. This will throw the pawl 87 down to the point where the pin 94 thereon will engage in the latch notch 92 on the latch 91, holding the pawl in its outward or disengaged position relative to the ratchet 68. At the same time the pin 106 is moved to the left, Fig. 3, and given a half turn so that it will be held in its left hand position, this retracts the projection 107 from the path of 70 the pawl 87 and its associated latch 91. With

the pawl 87 held in its retracted position and the pin projection 107 out of the path, the handle can be then swung around until the handle is on the right hand side of the hoist, the pawl 87 and its latch 91 being retracted sufficiently far to clear the arm 105 on the ring 97. If the handle, under these circumstances, is raised considerably until the latch 91 engages the stop pin 112, this will release the latch, in turn releasing the pawl 87, so that the pawl can now be biased into engagement with the ratchet. Under these circumstances, the load may be hoisted by oscillating the handle except, in this instance, the hoist pressure will be applied upwardly on the handle to rotate the ratchet 68 and shaft 65 in a counterclockwise direction.

If it be desired to lower the load, the adjusting handle 80 will be swung in a direction opposite to that shown in Fig. 2 to place the spring 76 under a biased tension to bias the pawl 71 out of engaging position with respect to the ratchet teeth of the ratchet 68. However, with the handle being held in its now elevated position the pawl 87 will be in position to engage the ratchet teeth, and by lowering the handle the rotation of the ratchet and the load wheel, under load, will be effected in a clockwise direction. When, however, the handle is lowered to its lowermost position, the pin 104 on the pawl 87 will strike the face of the arm 105, rotating this arm sufficiently to cause the holding pawl 71 to move into engagement with one of the teeth of the ratchet 68. At the same time the pawl 87 through the medium of this pin 104 will be depressed sufficiently far for the latch pin 94 on the pawl to engage in the notch 92 on the latch member 91, holding the pawl out of engaging position relatively to the ratchet teeth 68; and the handle may then be swung up freely, the load being held by the holding pawl until the handle is sufficiently raised for the latch 91 to engage the pin 112. This will release the pawl 87 permitting it to move into engagement with one of the teeth of the ratchet 68, again permitting the load to lower.

If it be desired to effect free chaining, the pawl 71 is biased into its disengaged position and the handle 84 is operated only to an intermediate point, that is, not raising the handle until the latch 91 reaches the pin 112. The pawl 87 will then be held out of engagement so that neither the holding nor load pawl are operative, and the chain and ratchet with the chain wheel may be freely moved.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A hoist structure including a housing mounting a shaft, a load supporting wheel on said shaft, a co-axial offset ratchet wheel thereon, a holding pawl pivoted on said housing for ratcheting engagement with said ratchet wheel, a spring normally biasing said pawl into ratchet engaging position, an operating handle pivoted on said housing in co-axial relation to said wheel, a load pawl pivoted on said handle, a spring on said handle engaging said load pawl for biasing it into

70 75

ratcheting engagement with said ratchet wheel, a latch pivoted on said handle in biased engagement with said last-mentioned spring movable into and out of latching engagement with said load pawl, a control member movable to reverse the tension on said first-mentioned spring to bias said holding pawl out of ratchet wheel engagement, and a control ring mounted for rotation on said shaft adjacent said ratchet wheel having a radially projecting camming member operably connected with said holding pawl engageable by said load pawl at the end of its load lowering stroke to effect holding pawl engagement with said ratchet wheel and engagement by said latch to be latched from ratchet wheel engagement during its return stroke.

2. A hoist structure including a housing mounting a shaft, a load supporting wheel on said shaft, a co-axial offset ratchet wheel thereon, a holding pawl pivoted on said housing for ratcheting engagement with said ratchet wheel, a spring normally biasing said pawl into ratchet engaging position, an operating handle pivoted on said housing in co-axial relation to said wheel, a load pawl pivoted on said handle, a spring on said handle engaging said load pawl for biasing it into ratcheting engagement with said ratchet wheel, a latch pivoted on said handle in biased engagement with said last-mentioned spring movable into and out of latching engagement with said load pawl, a control member movable to reverse the tension on said first-mentioned spring to bias said holding pawl out of ratchet wheel engagement, a control ring mounted for rotation on said shaft adjacent said ratchet wheel having a radially projecting camming member operably connected with said holding pawl engageable by said load pawl at the end of its load lowering stroke to effect holding pawl engagement with said ratchet wheel and engagement by said latch to be latched from ratchet wheel engagement during its return stroke, and a retractile pin movable in said housing into and out of the path of movement of said latch to be inoperative relative thereto when in one position and engageable thereby when in another position to unlatch said load pawl when moved to its other extreme position for ratchet wheel engagement.

3. A hoist structure including a housing mounting a shaft, a load supporting wheel on said shaft, a co-axial offset ratchet wheel thereon, a holding pawl pivoted on said housing for ratcheting engagement with said ratchet wheel, a spring normally biasing said pawl into ratchet engaging position, an operating handle pivoted on said housing in co-axial relation to said wheel, a load pawl pivoted on said handle, a spring on said handle engaging said load pawl for biasing it into ratcheting engagement with said ratchet wheel, a latch pivoted on said handle in biased engagement with said last-mentioned spring movable into and out of latching engagement with said load pawl, a control member movable to reverse the tension on said first-mentioned spring to bias said holding pawl out of ratchet wheel engagement, a control ring mounted for rotation on said shaft adjacent said ratchet wheel having a radially projecting camming member operably connected with said holding pawl engageable by said load pawl at the end of its load lowering stroke to effect holding pawl engagement with said ratchet wheel and engagement by said latch to be latched from ratchet wheel engagement during its return stroke, and a second

7 camming member on the opposite side of said ring from said first-mentioned member operative to actuate said holding pawl upon reversal of said load pawl.

4. A hoist structure including a housing mounting a shaft, a load wheel and ratchet on said shaft, a holding pawl positioned for ratcheting engagement with said ratchet, an operating handle pivoted on said housing in co-axial relation to said ratchet, a load pawl pivoted on said handle biased in ratcheting engagement with said ratchet, a load pawl latch operative to latch said load pawl out of ratchet engagement, a control member operative to bias said holding pawl out of ratchet engagement, a control ring engageable by said load pawl at the end of one stroke to move said holding pawl into ratchet engagement, and a projection on said housing engageable by said latch to release said load pawl for ratchet engagement at the end of its stroke in the opposite direction.

5. A hoist structure as defined by claim 4 wherein said control ring and holding pawl are provided with a free play pin and slot connection to freely permit biasing of said pawl into ratchet engagement and positively move said pawl to ratchet engagement when biased therefrom.

6. A hoist structure as defined by claim 4 wherein said control ring is provided with one projection operatively connected with said holding pawl, and an oppositely disposed projection, either of said projections being engageable by said load pawl for actuation to move said holding pawl to ratchet engagement and swing said load pawl out of ratchet engagement.

7. A hoist structure as defined by claim 6 wherein the projection on said housing consists of a transversely movable pin operable when retracted to permit said load pawl and its operating handle to be swung to the opposite side of said pawl in reversed position to engage said second-mentioned control ring projection.
